Primary Examiner—Bernard Ansher*Assistant Examiner*—Mitchell I. Siegel*Attorney, Agent, or Firm*—Darby & Darby[57] **CLAIM**

The ornamental design for a combined nasal adaptor and cap, as shown and described.

DESCRIPTION

FIG. 1 is a front and left side perspective view of a combined nasal adapter and cap showing our new design;

FIG. 2 is a front elevational view thereof, the undisclosed rear view being a mirror image;

FIG. 3 is a side elevational view thereof, the undisclosed opposite side being a mirror image;

FIG. 4 is a cross section taken on line 4—4 of FIG. 5 showing the cap alone for clarity of illustration;

FIG. 5 is a bottom plan view of FIG. 4;

FIG. 6 is a top plan view of FIG. 1;

FIG. 7 is a bottom plan view of FIG. 1;

FIG. 8 is an exploded front elevational view of FIG. 1;

FIG. 9 is a side elevational view of the nasal adapter shown without the cap for clarity of illustration, the undisclosed opposite side being a mirror image;

FIG. 10 is a top plan view of FIG. 9; and,

FIG. 11 is an exploded front elevational view of FIG. 9, shown for clarity of illustration;

FIG. 12 is a right side elevational view of the bottle with nasal adaptor removed, the left side elevational view being identical thereto;

FIG. 13 is a top plan view thereof;

FIG. 14 is a bottom plan view of the nasal adaptor shown in FIG. 11;

FIG. 15 is a front perspective view of the bottle shown in FIG. 12 with valve removed; and,

FIG. 16 is a top plan view thereof.
